UNITED STATES PATENT OFFICE.

CHARLES H. EDWARDS, OF SAGINAW, MICHIGAN.

TOY.

1,299,310.

Specification of Letters Patent. Patented Apr. 1, 1919.

Application filed December 9, 1918. Serial No. 265,975.

To all whom it may concern:

Be it known that I, CHARLES H. EDWARDS, a citizen of the United States, residing at Saginaw, in the county of Saginaw and 5 State of Michigan, have invented new and useful Improvements in Toys, of which the following is a specification.

This invention has reference to a wind operated toy.

10 An object of the invention is to produce a toy, in the nature of a whirligig comprising angularly disposed connected blades mounted on a shaft formed on the end of a handle, each of said blades being formed with vanes 15 designed to be contacted by the wind whereby by the blades are revolved around the shaft.

A further object of the invention is to produce a toy of this character in which the right angularly disposed blades are connected together without the employment of securing elements, the said blades, at the center thereof being formed with bulging portions that provide a hub for a shaft on which the blades are journaled, the blades 25 having their outer portions slotted and the material bounded by the slits being bent at desired angles to provide vanes and are designed to be contacted by air currents to revolve the blades, the speed at which the 30 device is revolved being regulated by the adjustment of the vanes.

It is a further object of the invention to produce a toy of this character which shall be of an extremely simple construction and 35 which may be cheaply manufactured and marketed.

The foregoing objects may be accomplished by a construction illustrated by the drawings, and in which:

40 Figure 1 is a perspective view of the improvement;

Fig. 2 is an approximately central longitudinal sectional view therethrough.

Fig. 3 is a plan view of one of the blades; 45 and

Fig. 4 is a similar view of the coöperating blade.

50 Preferably, and as disclosed by the drawings, a handle for the toy is constructed of wire and is indicated by the numeral 1. The handle may be twisted as disclosed by the drawings and the strands comprising the same formed in the shape of a flat substantially rectangular loop or widened por-

tion at the lower end of the handle to afford 55 a more efficient grip thereon. The handle 1, at its opposite end is extended at a right angle to provide a shaft 2 and on this shaft is journaled the wind wheel which is broadly designated by the numeral 3. The shaft, at 60 the portion thereof on which the wind wheel is journaled may be reduced or may be provided with flanges 4 which may be in the nature of washer members so that the wind wheel is held against movement in a longitudinal direction on the shaft.

The wind wheel comprises two blades of similar size and each constructed of a flat rectangular plate or sheet of any suitable material, thin metal, such as tin preferred, 70 but, of course, the blades may be constructed of card board or other material as desired.

The blades, for distinction are indicated by the numerals 5 and 6 respectively. Each of the blades, at the center thereof is formed 75 with an out-bulged portion 7 having a central opening therethrough, and these portions 7 provide what may be termed the hub of the wind wheel, the shaft 2 of course, being received through the hub. The blade 5, 80 at the center thereof is provided with spaced longitudinal slits 8 of a length corresponding with the width of the blade 6, and the blade 6 is adapted to be passed through these slits whereby to connect the same to the 85 blade 5 and arrange both of the blades at a right angle with respect to each other. When the blades are thus associated a pointed implement is forced therethrough, at preferably diagonally opposed points, 90 thus forcing the material of one of the blades into frictional contact with the material of the other blade and thus locking the blades together.

Both of the blades 5 and 6, outward of 95 their lapping or connected central portions are provided with spaced longitudinal and transverse slits, and the metal bounded by the said slits is bent at an inward angle, or at an angle in the direction of the handle 1 100 to provide vanes 9. The blades being constructed of bendable material, preferably, as stated, of tin, permit of the vanes being arranged at desired angles with respect thereto, so that the same may be adjusted to offer 105 the proper resistance to air currents to permit of the wheel being revolved by such contact at a desired velocity. Oil saturated

cotton may be placed in the hub for lubricating the shaft.

Having thus described the invention, what is claimed as new, is:

- 5 1. A wind toy comprising a wheel formed of two flat rectangular blades which lap at the central portions thereof, one of said blades having spaced slits through which the other blade passes, both of said blades 10 being punctured at the said lapping portions, each of the blades being centrally formed with an out-bulged portion providing a hub, a shaft received through said hub, an angle handle on said shaft, said blades, 15 outward of their lapping portions having pairs of longitudinal and transverse slits, and the metal bounded by said slits being

bent angularly with respect to the blades to provide adjustable vanes therefor.

- 20 2. A wind toy comprising a wheel formed of two flat rectangular blades which lap at the central portions thereof and which are connected together at their said central portions, each of the blades having centrally formed thereon an outbulged portion providing a hub, a shaft received through said hub, an angle handle on said shaft, said blades outward of their lapping portions having pairs of longitudinal and transverse slits and the material bounded by said slits being bent with respect to the blades to provide 25 adjustable vanes therefor.

In testimony whereof I affix my signature.

CHARLES H. EDWARDS.

Copies of this patent may be obtained for five cents each, by addressing the "Commissioner of Patents, Washington, D. C."
